CLAIM

The ornamental design for a hybrid vertical takeoff and landing flying automobile, as shown and described.

DESCRIPTION

FIG. 1 is a top perspective view of a hybrid vertical takeoff and landing flying automobile showing our new design;

FIG. 2 is a top perspective view of the hybrid vertical takeoff and landing flying automobile with wings extended;

FIG. 3 is a top perspective view of the hybrid vertical takeoff and landing flying automobile with four wheels on the ground and wings extended;

FIG. 4 is a top perspective view of the hybrid vertical takeoff and landing flying automobile with wings vertical;

FIG. 5 is a top perspective view of the hybrid vertical takeoff and landing flying automobile with four wheels on the ground and wings vertical;

FIG. 6 is a top perspective view of the hybrid vertical takeoff and landing flying automobile with wings extended and parachute launched;

FIG. 7 is a left side view of hybrid vertical takeoff and landing flying automobile shown in FIG. 1;

FIG. 8 is a right side view thereof;

FIG. 9 is a top view thereof;

FIG. 10 is a bottom view thereof;

FIG. 11 is a back view thereof; and,

FIG. 12 is a front view thereof.

The broken lines shown in the drawings illustrate portions of the hybrid vertical takeoff and landing flying automobile and forms no part of the claimed design.
